DESIGN FOR A TABLE TOP

Wolfgang Hoffmann, Batavia, Ill., assignor to
The Howell Company, St. Charles, Ill., a corporation of Illinois

Application June 26, 1939, Serial No. 85,696

Term of patent 3½ years

To all whom it may concern:

Be it known that I, Wolfgang Hoffmann, a citizen of the former Republic of Austria, residing at Batavia, in the county of Kane and State of Illinois, have invented a new, original, and ornamental Design for a Table Top, of which the following is a specification, reference being had to the accompanying drawing, forming a part thereof, in which

Fig. 2 is a top plan view thereof.

I claim:

The ornamental design for a table top, as shown.
